[57] CLAIM

The ornamental design for a covered oven pot, as shown and described.

DESCRIPTION

FIG. 1 is a top view of a covered oven pot showing our new design;

FIG. 2 is a side elevation thereof;

FIG. 3 is an end elevation thereof;

FIG. 4 is a bottom elevation thereof;

FIG. 5 is a side elevation thereof, partly in section, taken along the discontinuous section line 5—5 of FIG. 1 in the direction of the arrows;

FIG. 6 is a top view of the cover thereof;

FIG. 7 is a side elevation of the cover thereof;

FIG. 8 is an end elevation of the cover thereof;

FIG. 9 is a bottom elevation of the cover thereof;

FIG. 10 is a top view of the oven pot thereof;

FIG. 11 is a side elevation of the oven pot thereof;

FIG. 12 is an end elevation of the oven pot thereof; and

FIG. 13 is a bottom elevation of the oven pot thereof.
